UNITED STATES PATENT OFFICE.

HARRY W. JONES, OF ST. LOUIS, MISSOURI, ASSIGNOR TO SANFORD INVESTMENT CORPORATION, OF KNOXVILLE, TENNESSEE, A CORPORATION OF DELAWARE.

JOURNAL BOX AND AXLE.

Application filed June 28, 1926. Serial No. 119,080.

This improvement relates particularly to the axles, axle boxings and wheels of mine cars.

The object of the invention is to produce such a structure of elements shaped and inter-related for easy manufacture and assembling and separating, the finished structure having ample strength to resist wear due to rotation and to resist endwise thrust in either direction.

Among the features of the improvement are a tubular hub lining with provision for keeping that lining in position against tendency to move endwise; also provision for assembling the rollers on the axle before the hub is put into position around the rollers and axle; and also a new and effective means for holding the hub against outward movement on the axle; also the arrangement of parts in such manner as to minimize retaining wear on the wheel casting and the axle and place this wear on cheap, replaceable parts, namely, the locking keys and the renewable steel collar.

In the accompanying drawings,

Fig. 1 is a horizontal, upright longitudinal section along the axial line of an axle, axle box, hub and wheel structure embodying my improvement;

Fig. 2 is an upright, transverse section on the line, 2-2, of Fig. 1, looking toward the left;

Fig. 3 is an upright, transverse section on the line, 3-3, of Fig. 1, looking toward the left;

Fig. 4 is an upright, transverse section on the line, 4-4, of Fig. 1, looking toward the left;

Fig. 5 is an upright, transverse section on the line, 5-5, of Fig. 1, looking toward the left;

Fig. 6 is an upright section on the line, 6-6, of Fig. 1;

Fig. 7 illustrates the manner of placing the rollers and retaining ring in position to be moved into place on the axle preparatory to receiving the cup washer, the collar and the cross pin preparatory to placing the hub around those elements;

Figs. 8 and 9 illustrate other forms of means for engaging the hub on the axle;

Fig. 10 is an upright section on the line, 10-10, of Fig. 9, looking toward the right.

Referring to said drawings, A is a part of the axle. A¹ is the journal; and A² is a cir-

cumferential shoulder at the inner end of the journal. The journal is of uniform diameter.

B is the wheel. B¹ is the hub. B² is the wheel hub lining. B³ is the hub end wall 60 adapted to bear against the end of the journal. The lining is immovable in the hub. Its outer end bears against the shoulder, B⁴, formed on the interior of the hub. C, C are rollers arranged parallel to the journal and 65 occupying the space between the journal and the hub lining. Midway between their ends, the rollers have circumferential grooves, C¹. A retaining ring, C², surrounds the group of rollers within said grooves. Said ring serves 70 to retain the rollers on the journal preparatory to placing the hub in position on the journals and rollers.

A collar, D, surrounds the journal at the outer end of the latter. A cross pin, D¹, extends through the collar and the journal. Between the collar and the adjacent ends of the rollers, C, is an angle washer, D², which has an outward-directed flange, D³, which is adapted to bear against the adjacent ends of the rollers. Between the flanges, D³, and the collar, D, are two tangential locking keys, D⁴, the ends of which extend through the hub, B¹. (See Figs. 1, 2 and 3.) When there is outward thrust or drift of the 85 wheel, these locking keys bear against the inner face of the collar, D, that collar being held immovably by the cross pin, D¹. As above stated, the inward thrust or drift of the wheel is met by engagement between the 90 outer end of the journal and the inner face of the end wall, B³, of the hub.

An axle box, E, surrounds the journal between the inner end of the hub and the shoulder, A². The axle box has a flange, E¹, 95 surrounding the inner end of the hub. A washer-form wearing plate, E², is placed between the inner end of the hub and the adjacent upright face, E³, of the axle box. Between said wearing plate and the end of the hub lining, B², a washer, E⁴, surrounds the journal within the hub. This washer serves as a grease dam to prevent or retard flow of grease outward at the inner end of the hub. Said washer also serves as a means 100 for preventing the hub lining from moving endwise against the wearing plate, E², and cutting said plate. As above stated, the forward end of the hub lining, B², bears against the shoulder, B⁴, formed on the inner face of 110

the hub. Therefore the inner end of the lining is fixed relative to the hub.

The axle box is secured to the car bottom, F, as has heretofore been done.

5 The parts are assembled as follows:

The axle box and the axle and journal having been placed into position as shown in Fig. 1, the wearing plate, E³, and the washer, E⁴, are placed into position on the 10 journal, as shown in Fig. 7. Then the rollers are placed into the position shown in Fig. 7, the outer ends of the rollers approaching each other sufficiently to allow the retaining ring, C², to be moved inward over the group 15 of rollers and into the grooves, C¹. When the retaining ring has been thus placed, the rollers are to be tilted on the end of the journal to bring them parallel to each other and bear on the outer face of the journal. 20 Then the group of rollers and the ring are to be moved horizontally along the journal until the inner ends of the rollers meet the washer, E⁴. Now the retaining ring will hold the rollers in position. The angle 25 washer, D², is next brought and moved inward around the outer end of the journal until it bears against the ends of the rollers. Then the collar, D, is placed into position around the outer end of the journal. Then 30 the cross pin, D¹, is inserted through the collar and the journal.

Now the wheel is to be put into position by moving it horizontally inward over the collar, D, the angle washer, D², and the 35 rollers, C, until the end wall, B³, of the hub bears against the outer end of the journal and the inner end of the hub surrounds the washer, E⁴. The locking keys, D⁴, are now placed into position in the hub and in the 40 annular channel between the collar, D, and the angle washer flange, D³. Each locking key has at one end a head, D⁵, and at its other end a nut, D⁶.

The parts remain thus assembled until it 45 is desired to remove the wheel. Then the two locking keys, D⁴, are removed. Then the entire wheel may be drawn endwise away from the axle box and away from the washer, E⁴, rollers, C, angle washer, D², and the 50 collar, D, these several members remaining in position on the journal. If those members are to be removed, the first step will be the removal of the cross pin, D¹, for the release of the collar, D. When that has been done, 55 the angle washer and the rollers and the retaining ring and the washer, E⁴, and the bearing plate, E³, may be removed successively.

A grease receiving plug, G, may be 60 threaded into any suitable part of the hub wall, as shown in Figs. 2, 3 and 6. Said plug is tubular and is adapted to be engaged by a member on a grease gun or similar device, as is already known in this art.

65 In Fig. 8, the structure is the same as

shown by Figs. 1 and 6, excepting that a collar, D⁷, is substituted for the collar, D, of the previous form. This collar, D⁷, has at its outer side a notch, D⁸, which receives the cross pin, D¹.

In Figs. 9 and 10, the angle washer, D², is omitted and a collar, D⁹, is substituted for the collars, D and D⁷, already described. The collar, D⁹, is wide enough to allow placing the cross pin, D¹, midway between the 75 upright face of the collar and to form diametrically opposite and parallel channels, D¹⁰, in the transverse plane cutting the cross pin, said channels being of proper width and depth to receive the locking keys, D⁴.

It is now to be noted that the construction described allows easy manufacture of the axle and journal. If so desired, the axle and journal may be a unitary piece of equal diameter throughout excepting for the shoulder, A². Attention is especially asked to the fact that the outer end of the journal is not grooved or otherwise reduced circumferentially to provide for attachment of members concerned with the holding of the hub 90 against outward movement on the journal. This simplifies and cheapens manufacture and at the same time adapts the journal to resist transverse strains and impacts throughout all of the part of the journal 95 which is surrounded by the hub. The pressure exerted by the load is downward on the rollers, C, and also on the collar, D or D⁷ or D⁹. Instead of being transversely grooved or channeled or off set to make provision for holding the hub against outward movement, the journal is given a simple transverse bore only large enough to receive the cross pin, D¹.

In addition to serving to hold the group 105 of rollers in position on the journal when the hub is absent, the retaining ring, C², aids in the distribution of lubricant when the wheel is in position and rotates, the rotation of the wheel then causing rotation and revolution of the rollers, and engagement between the ring and the rollers and the hub lining causing rotation of the ring. During such movement of the ring, lubricant will be carried with the ring.

110 I claim as my invention:

1. In a structure of the kind described, the combination of a journal of uniform diameter, a collar surrounding the outer end of the journal, means securing said collar to the journal, rollers on the journal, a hub surrounding the rollers and collar, and locking keys extending through the hub and positioned to engage the collar, substantially as described.

115 2. In a structure of the kind described, the combination of a journal of uniform diameter, a collar surrounding the outer end of the journal, means securing said collar to the journal, rollers on the journal, a hub sur-

rounding the rollers and collar, locking keys extending through the hub and positioned to engage the collar, and a wearing plate and an axle box at the inner end of the hub, substantially as described.

3. In a structure of the kind described, the combination of a journal of uniform diameter, a collar surrounding the outer end of the journal, a cross pin seated in the journal and engaging the collar, rollers on the journal, a hub surrounding the rollers and collar, and locking keys extending through the hub and positioned to engage the collar, substantially as described.

15 4. In a structure of the kind described, the combination of a journal of uniform diameter, a collar surrounding the outer end of the journal, means securing said collar to the journal, rollers on the journal, a hub surrounding the rollers and collar and hav-

ing a fixed end wall extending across and adapted to bear against the end of the journal, and locking keys extending through the hub and positioned to engage the collar, substantially as described.

25

5. In a structure of the kind described, the combination of a journal, a collar surrounding the outer end of the journal, means securing said collar to the journal, rollers on the journal, an angle washer between the rollers and said collar, a hub surrounding the rollers, angle washer, and collar, and locking keys extending through the hub and tangentially across the angle washer, substantially as described.

35

In testimony whereof I have signed my name, this 22nd day of June, in the year one thousand nine hundred and twenty-six.

HARRY W. JONES.
